UNITED STATES PATENT OFFICE.

EDMUND BIGELOW, OF SPRINGFIELD, MASSACHUSETTS.

SODA-WATER APPARATUS.

Specification forming part of Letters Patent No. 22,697, dated January 25, 1859; Reissued August 6, 1867, No. 2,711.

To all whom it may concern:

Be it known that I, EDMUND BIGELOW, of Springfield, in the county of Hampden and State of Massachusetts, have invented a new and useful improved apparatus for drawing soda-water keeping and icing syrups, and distributing them by measure into the glasses used at the soda-counter; and I do hereby declare that the following is a full and exact description thereof, reference being had to the accompanying drawings and to the letters of reference marked thereon.

The nature of my invention consists of a set of reservoirs or vessels set on a common base as represented by Figure 3, a metallic hollow shaft running through a thimble set in ice chamber in Fig. 3, two arms leading from the head of the shaft through which the soda water flows and from which it is discharged in the ordinary way, which arms are represented on Fig. 2; and a self measuring faucet as shown in Fig. 4.

To enable others skilled in the art to make and use my invention I describe its construction and operation, as follows—

Fig. 1 represents a perspective view of the whole apparatus. Fig. 3 is a diagram view of the inside arrangement of the syrup fountain or caster. Fig. 2 is a transverse view of the whole apparatus.

The lines marked I is a thimble through which shaft E passes from the counter upward.

B is the base on which the cans stand.

R is a plate on which base B revolves around shaft E;

K is a plate through which shaft E passes, and to which it is secured by screws.

T is a nut screwed upon the shaft below the counter, and making the shaft firm, as a stand on which the fountain or syrup caster revolves.

X is the head of shaft E, and is made separate and drilled and screw cut to fit the shaft. Head X is also drilled for the arms S S to be attached by screw thread, giving flow way direct from the soda pipe to the stop valves N at the end of the arms.

G is the shaft of the faucet, connecting it with the reservoir.

B is the body of the faucet, A A the cap, D the valve rod, R a packing box, C a valve cast on rod D and fitting valve seat P.

J is a spiral spring which throws lower valve M into its place when the pressure is taken off the head of rod D.

H is a guide bar to rod D.

O is the flow port to pipe G, through which the fluid passes into the faucet.

N is a tube running through cap A A and extending to the top of the reservoir. Rod D is hollow, and is furnished with two vents one at Q and one at T. When rod D is at rest without pressure applied, and valve M is closed, vent T stands closed, being in, and closed by, the packing box R, and above the packing. The vent Q is always open.

Fig. 3 represents eight apartments for syrup, marked A A A. The circular chamber B, is for ice. C is a thimble in center of ice chamber.

The mode of using the apparatus is as follows. Shaft E is passed through a hole in the counter making flange or plate K the stand. The nut T, is screwed up under the counter till the shaft is firm. Plate R is slipped on and secured with set screws at the height at which the reservoir is to stand. The revolving plate or base to the cans is slipped down to plate R. The apron, as represented in perspective view, Fig. 1 being the part under the faucets, and covering the revolving apparatus, is put in place. The cans for syrup are put into position around the ice chamber and secured by a band and covered by case S S in Fig. 1, and a faucet is attached to each can. The reservoirs thus arranged are passed down the shaft, the shaft passing through thimble in the ice chamber. The head to shaft E, with arms S S attached is screwed to the shaft, and the cover being in two parts with opening at the top, the whole is in position for use. The lower end of shaft E having been connected with the soda fountain under the counter, soda water is drawn through arms S S in the ordinary way. The syrup reservoirs being filled with their appropriate syrups, the fluid flows through pipe G and fills faucet B Fig. 2. Rod D, being then pressed down quickly by the hand, valve C is brought firmly into its seat P, closing port O, and stopping the flow of syrup into the faucet. By the same movement of the rod D the valve M is opened, and vent T, in rod D, is carried below the cap A A, permitting a free entrance of air into the body of the faucet, and the syrup already in the faucet flows immediately into the glass. On removing the hand from rod D, spiral spring J, forces rod D back to its original position, bringing valve M to a bearing and opening

port O and closing vent T, and the faucet again instantly fills with syrup and may again be emptied by renewing the pressure on rod D, as before. The advantage derived from the vents Q and T in rod D is that they give an instantaneous and abundant supply of air to the faucet and cause the syrup to flow into the glass much more rapidly than it would if the air were supplied through vent tube N, alone, because vent pipe N is always filled with liquid to the same height as it stands in the reservoir—and on the other hand, if the air passage through rod D by the two vents were left open into the body of the faucet after the pressure was removed from rod D, and

valve M was closed, the syrup would be thrown out through that passage by the sudden refilling of the faucet.

What I claim as my invention and desire to secure by Letters Patents is—

1. The arrangement of a set of syrup cans, ice chamber and draft pipe, substantially as described.

2. I also claim the combination of a measuring faucet with the herein described and claimed arrangement of devices for drawing syrups and soda water. 25

EDMUND BIGELOW.
